US00D752963S

(12) **United States Design Patent**
Kaupp

(10) **Patent No.:** **US D752,963 S**
(45) **Date of Patent:** **** Apr. 5, 2016**

(54) **ANCHOR**

(71) Applicant: **fischerwerke GmbH & Co. KG**,
Waldachtal (DE)

(72) Inventor: **Andreas Kaupp**, Waldachtal (DE)

(73) Assignee: **fischerwerke GmbH & Co. KG**,
Waldachtal (DE)

(**) Term: **14 Years**

(21) Appl. No.: **29/520,015**

(22) Filed: **Mar. 10, 2015**

(30) **Foreign Application Priority Data**

Sep. 23, 2014 (EM) 002542779

(57) **CLAIM**

The ornamental design for an anchor, as shown and described.

DESCRIPTION

FIG. 1 is a perspective view of an anchor showing my new design.

FIG. 2 is a top view thereof.

FIG. 3 is a bottom view thereof.

FIG. 4 is a left side view thereof.

FIG. 5 is a right side view thereof.

FIG. 6 is a front view thereof; and,

FIG. 7 is a rear view thereof.

The broken lines in the drawings illustrate portions of the Anchor and form no part of the claimed design.

1 Claim, 4 Drawing Sheets
